TOY MUSICAL INSTRUMENT

Gustav Proelsdorfer, Newark, N. J.

Application April 18, 1939, Serial No. 268,498

2 Claims. (Cl. 84—375)

This invention relates to improvements in toy musical instruments, and the invention has reference, more particularly, to toy instruments provided with vibratory reeds for producing musical sounds.

The invention has for an object to provide a simple, easily made and inexpensive toy musical instrument body including novel means for assembling therewith and retaining in operative relation thereto the reed plate element by which the musical tones are produced.

The invention has for another object to provide a toy musical instrument comprising a tubular paper or cardboard body into which the breath of the player may be blown to escape through vents or openings in the side thereof, novel means being provided for interposing, between the interior of the body and said vents or openings, the vibratory reeds by which the desired musical tones are produced; the sounding of the reeds being controlled by selectively stopping and opening the side vents or openings by means of the fingers, or by means of manipulatable mechanical stops.

The invention has for another object to provide a toy musical instrument of the kind mentioned which is of greatly simplified design and of low cost construction, and wherein the means for operatively mounting a reed plate therein is of such character as to considerably reduce the labor and cost of production, while at the same time so arranging and closely disposing the reed plate relative to the vents or openings that the reeds carried by the plate are respectively operatively associated only with the respective vents or openings by which they are served, without necessity for furnishing partitioning or air flow interrupting means between adjoining vents or openings and their associated reeds; all whereby by the sounding of reeds other than the desired reed is prevented when a given vent or opening is opened.

Other objects of the invention, not at this time more particularly enumerated, will be understood from the following detailed description of the same.

Illustrative embodiments of this invention are shown in the accompanying drawings, in which:

Fig. 1 is an elevational view of one embodiment of a toy musical instrument made according to this invention; Fig. 2 is a fragmentary elevational view of the instrument body with parts broken away and shown in section so as to disclose internal construction, said view being drawn on an enlarged scale; Fig. 3 is a longitudinal sec-

tional view, taken on line 3—3 in Fig. 2; Fig. 4 is a transverse sectional view, taken on line 4—4 in Fig. 1, but drawn on an enlarged scale.

Fig. 5 is a transverse sectional view of a modified form of the toy musical instrument structure; and Fig. 6 is also a transverse sectional view of another modified form of the instrument.

Fig. 7 is a fragmentary elevational view of still another modified form of the instrument structure; and Fig. 8 is a transverse sectional view thereof, taken on line 8—8 in Fig. 7.

Similar characters of reference are employed in the above described views, to indicate corresponding parts.

In one illustrative embodiment of this invention, the novel toy musical instrument comprises a tubular body A having affixed to one end thereof a suitable mouthpiece B, provided with an axial passage C, and having, affixed to its opposite end, an imperforate closure member or plug D, the outer end portion of which is suitably shaped to simulate the appearance of a flared or bell-shaped outer end of a conventional musical instrument.

In a preferred embodiment of the invention, the tubular body A is made of paper, cardboard or the like, in such manner as to provide a plurality of concentrically related plies, comprising an outer ply 10, and intermediate ply 11 and an inner ply 12. Provided in the outer ply 10 is a series of longitudinally spaced vents or openings 13, the number of which may be optionally varied according to the type of conventional musical instrument to be simulated. Ordinarily the vents or openings would be eight in number, corresponding to the number of notes in a major musical scale.

The reference character 14 indicates a reed plate. This reed plate usually comprises a rectangular metallic strip or plate having longitudinally extending air passage slots 15 corresponding in number and spacing to the number and spacing of the vents or openings 13 with which the body section A is provided. Affixed to the underside of said plate 14 are the butt portions 16 of vibratory reeds 17. Said reeds 17 are respectively registered in alignment with the respective air passage slots 15 so as to be vibrated, with musical tone producing effect, when air is permitted to pass through said slots and thence outwardly through an associated vent or opening 13 in the outer ply 10 of the body A.

Formed in the intermediate ply 11 of the body A is an elongated opening 18 which is sized to fit the reed plate 14, so that the latter may be

lodged therein. Formed in the inner ply 12 of the body A is an elongated opening 19 which is of less length and width than are the corresponding dimensions of said opening 18 of said intermediate ply 11, so that, when said opening 19 is registered and aligned with said opening 18, a seating ledge 20 is provided upon and by which the side and end marginal portions of the reed plate 14 are supported, when the intermediate and inner plys 11 and 12 are respectively telescopically assembled together and, in turn, entered within the outer ply 10 to assemble the various parts together in operative relation so as to produce the completed tubular body of the musical instrument.

It will be observed that the structure described is not only very simple and inexpensive per se, but also provides a very simple and efficient means for supporting the reed plate 14 relative to the control vents or openings 13, whereby the reed plate is not only strongly and immovably held in position but is likewise so disposed in such close underlying relation to the outer ply 10 as to substantially avoid intercommunicating air passages between any given vent or opening 13 and reeds other than the reed directly underlying said vent or opening, i. e., between said given vent or opening 13 and reeds longitudinally removed therefrom. By reason of such structural arrangement, the path of least resistance of air flow from the interior of the body A to any given opened vent or opening 13 lies only past and through the reed and associated reed plate air passage slot 15 which is located directly beneath and in intended operative relation to said given vent or opening 13. By reason of this construction, necessity for introducing partitioning material or means intermediate adjacent associated vent openings and sounding reeds is avoided, and consequently undesired sounding of any reeds except the particular reed governed by the opening of a given vent or opening 13 is eliminated.

As shown in Fig. 1, if it be so desired, manipulatable mechanical stop means of any well known construction may be employed to normally close the vents or openings 13 of the instrument, or these vents or openings may be closed and opened merely by application of the player's fingers thereto. An illustrative form of manipulatable mechanical stop means comprises, a base plate 21 suitably affixed to the exterior of the body A adjacently parallel to the row of vents or openings 13 thereof. Struck up from said base plate are fulcruming ears 22 to cooperate with corresponding hinge ears 23 with which the finger levers 24 of vent or opening stop members 25 are provided. Said fulcruming ears 22 and hinge ears 23 are pivotally joined by a hinge pintle wire 26 arranged to extend therethrough. Spring means 27 is provided in operative relation to each finger lever 24 adapted to yieldably turn the same about its pivotal connection so as to normally hold its stop member 25 in closed relation to the vent or opening 13 served thereby. By selectively pressing upon the free end portions of the finger levers 24, the stop members 25 may be moved to vent uncovering position as required.

Referring now to Fig. 5 of the drawings, a somewhat modified construction of the tubular body A is shown, the same comprising a two-ply structure consisting of an outer ply 28 and an inner ply 29. The outer ply 28 is provided with the row of longitudinally spaced vents or openings 30. Formed in the wall of the inner ply 29, to underlie the row of vents or openings 30 in said outer

ply 28, is a longitudinally extending depressed portion or inwardly offset portion 31 adapted to provide, beneath the outer ply 28, a trough-like seat 32 of a length and width adapted to conform to the reed plate 14. Said reed plate 14 is lodged in said seat 32 so as to be immovably held therein with its air passage slots 15 and associated reeds 17 respectively operatively related to and beneath the respective vents or openings 30. The bottom of said depressed or offset portion 31 is provided with a longitudinal opening 32' of less width and length than the reed plate 14, whereby air flow communication is established between the interior of the body A and the air passage slots 15 of said reed plate. It will be obvious that this modified construction of body A possesses all the advantages of the first described construction, while at the same time being somewhat simpler in form, and requiring somewhat less material in the make up of the tubular body.

A still simpler construction of tubular body A is shown in Fig. 6, wherein the same comprises a single ply tubular body 33, having a row of longitudinally spaced vents or openings 34. In this construction, the reed plate 14 is disposed against the inner side of the body 33 so that its air passage slots 15 and associated reeds 17 respectively underlie the respective vents or openings 34. Means are provided for retaining the reed plate in place as so disposed, which in one form comprises spaced transverse staples 35, the legs 36 of which are driven inwardly through the material of the body 33 and so as to straddle the reed plate 14, whereupon the free end portions of said legs 36 are turned angularly to provide clenching arms 37 to engage over the underside of the reed plate so as to retain the same in place against the inner surface of the tubular body 33. It will be apparent, that as thus disposed and held closely adjacent to the inner surface of said tubular body 33, effective intercommunication between any given vent 34 and reeds longitudinally removed therefrom is avoided, in the same manner and with the same advantages already above referred to.

In Figs. 7 and 8 there is shown another construction of simple form, similar to that of Fig. 6, wherein the instrument body comprises a single ply tube 38 having the longitudinally spaced vents or openings 39. The reed plate 14 is positioned against the inner side of the tubular body 38 so that its air passage slots 15 and associated reeds 17 respectively underlie the respective vents or openings 39. The means for securing the reed plate 14 in place comprise tubular metallic eyelets 40 having annular flanges 41 at their outer ends, and diametrically opposite clenching lugs 42 extending from their inner ends. These eyelets 40 approximate in depth the thickness of the wall of the tubular body 38, and the inside diameters thereof approximate the width of the reed plate 14, while their outside diameters approximate the diameters of the vents or openings 39, so as to be adapted to be entered therethrough in fitting relation thereto. To assemble the elements of the structure, the eyelets 40 are respectively inserted through the several vents or openings 39 until the flanges 41 seat upon the marginal portions of the latter. When the eyelets 40 are thus positioned, the clenching lugs 42 thereof will straddle the sides of the reed plate 14, whereupon said clenching lugs are turned angularly inward over and upon the underside of said reed plate, whereby the same serve to securely retain the reed plate in place against the inner

surface of the tubular body 38, with the reeds and air passage slots thereof in operative relation to the several vents or openings 39.

Since many changes and modifications of the 5 toy musical instrument, in addition to those already mentioned, and many apparently widely different embodiments of this invention could be made without departing from the scope thereof as defined in the following claims, it is intended 10 that all matter contained in the foregoing description or shown in the accompanying drawings shall be interpreted as illustrative and not in a limiting sense.

I claim:

- 15 1. In a toy musical instrument, a tubular body comprising concentric outer and inner portions, the outer portion having longitudinally spaced vents pierced therethrough, the inner portion having an outwardly open seating channel means, a reed plate having air passage slots and vibratory reeds affixed thereto with their free ends registered over said slots, said reed plate being seated in said seating channel means so as to be held thereby flatly and closely contiguous to the 20 under side of said outer portion with its slots and reeds closely underlying the vents of the latter,
- 25

and said seating channel means having an opening in the bottom thereof for communicating air from the tubular body interior to said air passage slots of said reed plate.

2. In a toy musical instrument, a tubular body comprising a plurality of concentric contiguous sections including an outer section having longitudinally spaced vents pierced therethrough, an intermediate section, and an inner section; a reed plate having air passage slots and vibratory reeds 10 affixed thereto with their free ends registered over said slots; said intermediate section having a longitudinal opening sized to fit and receive said reed plate therein, whereby the latter is disposed flatly and closely contiguous to the inner side of 15 said outer section with its slots and reeds closely underlying the vents of the latter; and said inner section having a longitudinal opening of less over all dimensions than those of the opening of 20 said intermediate section and adapted to be aligned with the latter, to thereby provide supporting ledge means for said reed plate and means for communicating air from the tubular body interior to said air passage slots of said reed plate.

GUSTAV PROELSDORFER. 25
